HOUSING FOR A COOKING APPARATUS

Walter Koziol, Russell, Ill., assignor to Beatrice Foods Co., Chicago, Ill.

Filed May 8, 1972, Ser. No. 251,573

Term of patent 14 years

Int. Cl. D7—02

U.S. Cl. D7—109

FIG. 1

FIG. 3

FIG. 2

FIG. 1 is a perspective view of the housing for a cooking apparatus showing my design;

FIG. 2 is a front view in elevation of the housing for a cooking apparatus shown in FIG. 1;

FIG. 3 is a view in side elevation taken along line 3—3 of FIG. 1; and

FIG. 4 is a back view in elevation of the housing for a cooking apparatus shown in FIG. 1.

The broken lines are shown for illustrative purposes only and form no part of the claimed design.

I claim:

The ornamental design for a housing for a cooking apparatus, substantially as shown and described.
